US00D697503S

(12) **United States Design Patent**
Melanson et al.

(10) **Patent No.:** **US D697,503 S**
(45) **Date of Patent:** **** Jan. 14, 2014**

(54) **CASE FOR ELECTRONIC DEVICE**

(71) Applicants: **Christopher Melanson**, Fort Collins, CO (US); **Dustin Rodriguez**, Fort Collins, CO (US); **Patrick Nelson**, Fort Collins, CO (US)

(72) Inventors: **Christopher Melanson**, Fort Collins, CO (US); **Dustin Rodriguez**, Fort Collins, CO (US); **Patrick Nelson**, Fort Collins, CO (US)

(73) Assignee: **Otter Products, LLC**, Fort Collins, CO (US)

(**) Term: **14 Years**

(21) Appl. No.: **29/441,681**

(22) Filed: **Jan. 8, 2013**

(51) LOC (10) Cl. **14-03**

(52) U.S. Cl.

USPC **D14/250**

(58) **Field of Classification Search**

USPC D14/250-253, 440, 203.3-203.7, 217, D14/496, 248, 238.1, 240, 447, 341-347, D14/444; D13/103, 107-108, 119; D3/201, D3/218, 247, 269, 273, 301, 303; 248/309.1, 371, 176.3, 668; 361/679.56, 679.3, 679.25, 816; 379/426, 433.11, 455; 455/575.1, 455/575.8; 206/305, 320; 320/108, 115; 429/96; 220/4.02; 150/165

(57) **CLAIM**

The ornamental design for a case for electronic device, as shown and described.

DESCRIPTION

FIG. 1 is a first rear isometric view of a case for electronic device showing our new design;

FIG. 2 is a rear view thereof; and,

FIG. 3 is a second rear isometric view thereof.

The broken lines depict unclaimed environment. The broken lines form no part of the claimed design.

1 Claim, 3 Drawing Sheets

FIG. 1

FIG. 2

FIG. 3
